UNITED STATES PATENT OFFICE.

JOSEPH WEATHERBY, OF NEW CUMBERLAND, PENNSYLVANIA, ASSIGNOR TO THE ELECTRIC ORE SEPARATOR COMPANY, OF NEW CUMBERLAND, PENNSYLVANIA, A CORPORATION OF DELAWARE.

ORE-CONCENTRATOR.

1,071,839.

Specification of Letters Patent.

Patented Sept. 2, 1913.

Application filed August 1, 1912. Serial No. 712,794.

To all whom it may concern:

Be it known that I, JOSEPH WEATHERBY, of New Cumberland, in the county of Cumberland and State of Pennsylvania, have invented certain new and useful Improvements in Ore-Concentrators; and I do hereby declare the following to be a full, clear, and exact description of the same, reference being had to the accompanying drawings, forming a part of this specification, and to the figures and letters of reference marked thereon:

My invention relates to ore concentrators and has for its object to impart effective weight to permeable ore particles of a low magnetic susceptibility, the invention being particularly adapted to pulsating or shaking tables for the separation of ore mixtures having such slight difference in specific gravity that they cannot be separated by the ordinary operation.

A further object is to provide a cheap and effective means to quickly precipitate the permeable particles of ore in so-called slimes and to bring about a recovery of values that are at the present time washed away and lost.

It is now generally accepted as a fact that all substances are affected to a greater or lesser degree by magnetism and with recently developed machines many minerals heretofore considered non-magnetic or not affected by magnetism have been separated by the action of a highly concentrated magnetic field.

My present invention provides a means whereby the ore mass passes through highly concentrated fields during its progress over a shaking table, the arrangement being such that permeable particles according to their degree of susceptibility will be deflected from their normal course by the combined action of gravity and magnetism, the effect being as though their specific gravity was suddenly increased many times above normal.

I do not limit my invention to any particular form of table and the accompanying drawings show only some of the many forms of apparatus which may be utilized.

In the drawings Figure 1 is a top plan view of a shaking table showing one embodiment of the invention. Fig. 2 is a top plan view of shaking table showing another arrangement of the magnet poles in rela-

tion to the riffles. Fig. 3 is a sectional elevation showing the arrangement of magnet with its adjustable supports, the concentrating magnetic terminals on the table deck, and the armature mounted under the table. Fig. 4 is a front view of an adjustable timing mechanism to properly space the magnet pulsations. Fig. 5 is a sectional elevation of the timer shown in Fig. 4. Fig. 6 is a detail section on an enlarged scale of a portion of the table and magnetic circuit terminals. Fig. 7 is a plan illustrating a modified arrangement.

Like reference letters and numbers in the several figures indicate the same parts.

The apparatus shown in the drawings with the exception of the magnetic equipments is a well known type of longitudinally differential reciprocating table or concentrating surface disposed in a horizontal position in a line parallel to its motion and adjustably inclined transversely with a pulp feeding device (1) and a clear water box 2 for supplying a proper amount of dressing water to the table 3. The concentration and delivery of the concentrates is effected by the action of gravity influenced by the flow of dressing water which stratifies the particles according to their relative specific gravity, and carries off the gangue while the differential reciprocating movement of the table produced by the usual mechanism 4 termed a head motion, causes the travel, stratification and delivery of the values or concentrates at the lower left hand corner. The surface of the table, termed the deck, is partially riffled and partly unriffled. The motion necessary to be imparted to the deck of a concentrating table of the type shown in the drawings consists in moving it substantially longitudinally of the riffle cleats 5 upon its surface, and toward the concentrates discharge end from a position of comparative rest with a gradually accelerated speed to the end of the stroke and reversing the direction quickly with a maximum speed during the return to the position of comparative rest at the beginning of the forward stroke. This has the desired effect of agitating and inducing the stratification of the settling material which is caught in the channels between the riffles cleats 5, and advancing the same at each forward stroke of the mechanism toward the riffle tips with a

step-by-step progression. The cross flowing wash water accomplishes the final cleaning and removal of gangue as the material approaches and passes the riffle tips, and the heavier concentrates, in the order of their specific gravities, pass out upon the cleared ore plane, and are carried forward thereupon to the concentrates discharge end of the deck and into the concentrate box, while the tailings are discharged to the waste. Should there be but a slight difference in the specific gravity of the material to be separated, the method as above described will not be effective. For illustration, an ore containing a mixture of zinc blende, pyrite, and serpentine rock is an ore whose content has but little difference of specific gravity, and so far as I know has never been successfully separated on a shaking table. The separation of such a mixture of materials will be later described in accordance with my invention.

Suitably mounted and rigidly supported in the deck of the table are a series of parallel soft iron strips or bars 6 of triangular cross section. These strips or bars are suitably spaced apart disposed in a horizontal plane and can be parallel or diagonal with the motion, suitable to the table upon which they are employed. The bars for forming magnetic riffles as they will be hereinafter termed, penetrate the deck and are suitably fastened on their under side to a thin soft iron plate 6' which in turn is securely bolted to the wood of the table deck. The upper surface of the magnetic riffle bars can be either flush with or extend slightly above the surface of the deck and terminate in sharp knife-like edges 6''. The edges produce highly concentrated areas in the magnetic field caused by the converging lines of force.

Adjustably mounted above the deck are the powerful magnets 7 with windings and pole pieces 7^b and 7^c extending parallel with and suitably adjusted above the magnetic riffles. The lower faces of magnetic pole pieces are smooth plain surfaces with their edges rounded off to prevent upward convergence of lines of force to sharp edges of the pole. To decrease the reluctance and form a path for the magnetic circuit without interfering with the free movement of the deck, an iron plate 8^a of ample capacity is mounted below and suitably spaced from the deck. It will now be noted that a highly concentrated magnetic field is formed by the converging lines of force to and through the sharp edges of the magnetic riffle bars whereby the action of gravity on any susceptible material will be greatly augmented.

The magnet 7 is rigidly secured at its top to cross beams 8 and 8' which in turn are adjustably mounted on pedestals 9. The pedestals 9 are of pipe screwed into a floor

flange 9^a at the base, with a cap shaped hand wheel 9^b supporting a lead screw 9^c in its center at the top. The pedestal pipe 9 also has slots 9^d cut in opposite sides to permit the projections 9^e of adjusting nut 9^f to extend through its wall. The cross beams 8 are forked at their ends and machined to form bearings for stud nut projections 9^e. By turning the hand wheels 9^b the adjusting nuts are raised or lowered permitting a nicety of spacing of the air gap between the pole pieces and magnetic riffles.

As before stated, all substances can, to a varying degree, be acted upon by magnetism. It is true that many of them are less permeable than air. Such substances less permeable than air will be termed diamagnetic. These substances when subjected to a powerful magnet field seem to be repelled. Some minerals can be made strongly magnetic by roasting while others are not so affected. The substance that can be noticeably attracted to a varying degree according to the strength of a concentrated magnetic field will be hereinafter called para-magnetic substances. Para-magnetic substances tend to follow the converging lines of force in a concentrated magnetic field and as shown in Fig. 6 when the current is turned on the magnet the convergence of the lines of force is downward to the magnetic riffle bars thus causing the para-magnetic ore particles to be attracted downward to the riffles, thus augmenting their effective weight. It will now be noted that as long as the current flows through the magnetic coils the para-magnetic particles will be attracted to the magnetic riffles, and a means must therefore be provided for accurately timing the period when the current is connected with or cut off the magnet so that the ore particles can progress to their discharge.

Figs. 4 and 5 show a form of timing mechanism 10 that will accurately perform the above stated function. This mechanism will hereinafter be termed the timer. Suitably housed within a casing 10^a is a revolving pair of fan shaped adjustable contact disks 10^b and 10^c. 10^b is rigidly forced upon the timing shaft 10^d while 10^c is suitably journaled upon 10^b. Contact disk 10^b has a lock screw 10^e extending through an adjusting slot 10^f in the contact disk 10^c. The contact disks can, by loosening the lock screw, be adjusted to lengthen or shorten the time of contact. Suitably mounted upon but electrically insulated from the casing 10^a is a contact maker spring 10^g with a contact maker 10^h. The contact maker spring is provided with a binding post 10ⁱ to which the conducting wire is attached. The loose end of the contact spring rests upon an insulated adjusting screw 10^j which

is also mounted upon the inside of the casing 10^a. The casing 10^a is journaled upon the timing shaft 10^d by ballbearing 10^e and is intended to be rotated a short distance either back or forward by lever 10^f to perform the function of either advancing or retarding the current in the magnet. The timer 10 is mounted on the end of the eccentric shaft of the head motion 4 by forcing the socket 10^g over the end of the eccentric shaft and locking with a set screw. It will of course be understood that the position of the contact disks must be accurately placed in proper relation with the reciprocating motion of the table before it is locked into place. The timer can be connected either directly in the circuit with the magnet where only small currents are required for certain ores, or when large currents are used on the magnets for lesser permeable ores it is to be used in a local circuit operating any ordinary or preferred form of oil relay switch. In the latter case the current would be of such strength that it would burn and destroy the contacts of the timer if allowed to pass therethrough.

A rheostat such as S, Fig. 1, is also preferably placed in the main magnet circuit to regulate the strength of the current and therefore the strength of the magnetic field as is well understood by those skilled in the art. Different para-magnetic minerals in the ore mixture will, as a rule, respond to different strengths of field and in addition to regulating the strength of the field more than one magnet with differing strengths of field may be required, one following the other to bring about a complete separation of all the minerals as shown for example in Fig. 7, where two magnets A and B are employed.

It sometimes so happens that mineral is so weakly para-magnetic that while its effective weight when in a concentrated field is appreciatively changed it will only stick to the magnetic riffle bars slightly. In this case it will not be necessary to pulsate the current on the magnet that governs this particular mineral as the differential reciprocating motion of the table will be sufficient to progress this mineral to its discharge. For another illustration, certain minerals to be concentrated contain quite a quantity of strong magnetic material such as black sand. A magnet with a comparatively weak field called a first magnet (A in Fig. 7, for example) is to be placed over the table ahead of all the rest of the strong magnets, and an alternating current of medium frequency used on this magnet as shown at T, Fig. 7, to vibrate the magnetic particles to prevent their entraining other values and gangue in their progress to the discharge. In the case of slimes having permeable ore particles the magnets and magnetic riffles

are so arranged that the water containing the values flow through the concentrated field. The values will be immediately precipitated to the riffles while the gangue goes on with the water.

Having described the mechanism and its action I will now describe the action of the ore mixture containing zinc blende, pyrite and serpentine rock, with and without the magnetic influence as is shown on the accompanying drawings, reference being had to Fig. 1 and Fig. 2. There is but very little difference between the specific gravity of these minerals. For illustration, the serpentine rock will be considered as 1, the zinc blende between 1 and 1.50 and the pyrite between 1.50 and 2. The pyrite being slightly the heavier. In Fig. 2 the areas between the dotted lines on the table are the stratified areas that would normally occur when the table is operated without magnetic action. G denotes the gangue strata, M the middlings strata, Z the zinc strata and P the pyrite strata. If the table be started in operation without the magnets being energized the ore feeding on the table deck 3 from the feed box 1 will progress along the riffles and stratify. The heavier particles advance out on the deck according to their specific gravity, and the lighter particles stay closer to the riffle tips. The gangue partly mixed with zinc particles will take a position in the space G. The middlings particles which are both gangue and zinc will advance along the space marked M. The zinc partly mixed with pyrite will advance along the Z space and the pyrite partly mixed with zinc will progress along the P strata. It will thus be seen that the separation effected is not satisfactory owing to the mixed condition of the products. The action of the ore mixture when the current is turned on the magnet is substantially as follows: The gangue being a dia-magnetic substance will not be retarded in its normal flow. The zinc blende is more para-magnetic than the pyrite, and will be acted upon by a weaker concentrated magnetic field than the pyrite. The table being in operation all the ore is stratifying and flowing through the gap between the upper ends of the pole pieces and the magnetic riffles. When the current is turned on and gradually regulated by the rheostat it is noted that all the zinc particles change their normal course and progress to the discharge underneath the magnet poles while the gangue and pyrite which is not affected with this strength of field follow a different path. The results are due to the fact that the zinc particles on the comparatively slow forward stroke of the table are strongly attracted downward by the converging lines of force in the concentrated magnetic field, therefore having their effective weight changed.

and when the table deck is now at the end of its forward stroke, the current is suddenly released and the table deck rapidly jumps back to its starting position where the current is again established for the next forward stroke. The zinc particles advance thus with the table but are released during the return movement whereby they are progressed to their discharge under the magnet poles. The stratification of the ore on the table is completely changed, since the zinc is removed from its old position in the strata marked Z to the upper part of the table under the magnet poles. The gangue takes its old position in strata marked G but is free from zinc. The old middlings strata M will disappear and will be gangue, owing also to zinc being removed. Since the zinc strata is removed the pyrite can have the freedom of space Z and will concentrate clean. There will probably be a narrow ribbon of pyrite middlings which can be returned to the ore feed.

In the table shown in Fig. 2 there is a slightly different arrangement of parts but with a similar action as above described. Only the acting surfaces of the pole pieces 7^a and 7^b of the magnets are shown for the sake of clearness. Two sets of wood riffles are shown. The regular set at the head end of the table and a supplementary set S on the upper side of the discharge end. The two sets of wood riffles are joined by magnetic riffles under the short pole pieces. The wood riffles on the discharge side of the table are comparatively deep. Their object is to receive the concentrate from under the magnet poles and safely convey it to the discharge.

It will be understood that any number of magnets with varying magnetic strength can be used to separate the various ore values in a mixed mass on the same table without departing from the broad idea of this invention.

Having thus described my invention, what I claim is:

1. In an ore concentrator, the combination with a transversely inclined longitudinally differentially reciprocatory dressing table having incorporated therein longitudinal strips of magnetic metal and means for differentially reciprocating said table horizontally to effect stratification and separation of the material thereon in divergent paths due to the difference in specific gravity of the elements composing the material, of a fixed magnet mounted above the table and having a pole terminal with an extended face in proximity to and above the magnetic strips in the table, whereby elongated magnetic fields are formed in which the lines of force converge toward the ore supporting surface of the table.

2. In an ore concentrator, the combination

with a transversely inclined longitudinally differentially reciprocatory dressing table having incorporated therein longitudinal strips of magnetic metal and means for differentially reciprocating said table horizontally to effect stratification and separation of the material thereon in divergent paths due to the difference in the specific gravity of the elements composing the material, of a fixed magnet mounted above the table and having a pole terminal with an extended face in proximity to and above the magnetic strips in the table, and a fixed armature located below and in proximity to the under surface of the table, whereby elongated magnetic fields are formed with the lines of force converging toward the ore supporting surface of the table.

3. In an ore concentrator, the combination with a transversely inclined longitudinally differentially reciprocatory dressing table having its ore supporting surface provided with riffles, and means for differentially reciprocating said table horizontally and feeding the ore over said table to effect stratification and separation of the material in divergent paths, due to the difference in specific gravity of the elements composing the material, and strips of magnetic metal incorporated in and movable with the table, of a fixed magnet located above the table and having a pole terminal with an extended face in proximity to and above the magnetic strips whereby elongated magnetic fields are formed in the ore path with the lines of force in said fields converging toward the ore supporting surface of the table.

4. In an ore concentrator, the combination with a transversely inclined longitudinally differentially reciprocatory dressing table having its ore supporting surface provided throughout a portion of its area only with riffles and means for differentially reciprocating said table and feeding the ore over the same to effect stratification and separation of the material of the ore in divergent paths due to the difference in specific gravity of the elements composing the ore, of means for creating a series of elongated concentrated magnetic fields in the ore path over the unriffled portion of the table only, the lines of magnetic force in said fields converging toward the ore supporting surface, whereby the ore will be subjected to a preliminary gravity separation uninfluenced by magnetic action and final stratification and separation is effected under the combined influence of magnetic action and gravity on the plane portion of the table.

5. In an ore concentrator, the combination with a dressing table having a portion of its surface plane and a portion provided with riffles, means for imparting horizontal movements to the table and feeding the ore over the same to effect stratification and sep-

- aration of the ore in divergent paths due to the difference in specific gravity of the elements composing the ore, and strips of magnetic metal incorporated in the unriﬄed portion 5 of the table, of ﬁxed magnets having pole terminals with extended faces in proximity to and above the magnetic strips in the table, whereby the ore will be preliminarily subjected to separation in the riﬄed portion 10 of the table uninfluenced by magnetism and then subjected to separation on the plane portion of the table under the inﬂuence of the magnetic ﬁelds.
6. In an ore concentrator, the combination 15 with the reciprocating dressing table having two sets of riﬄes extending longitudinally thereon, the sets being spaced longitudinally from each other, and the arrangement being such as to cause travel in divergent paths of the particles of different 20 effective weight, of means for creating a series of concentrated magnetic ﬁelds in the path of the ore between the two sets of riﬄes.
7. In an ore concentrator, the combination 25 with the reciprocating dressing table having two sets of riﬄes extending longitudinally thereon with the sets spaced longitudinally from each other, the arrangement being such as to cause travel in divergent paths of the particles of different 30 effective weight, of a magnet located in proximity to the surface of the table between the sets of riﬄes, and concentrated 35 magnetic circuit terminals for causing the lines of force to converge toward the ore supporting surface.
8. In an ore concentrator, the combination 40 with a transversely inclined longitudinally differentially reciprocating table having in succession stratifying and dressing zones and means for imparting reciprocating movements thereto and for feeding the ore over the same to effect stratification and 45 separation due to the difference in specific gravity of the particles composing the ore, of means for creating concentrated magnetic 50 fields of alternating polarity in the ore path during the movements of the table, whereby magnetically susceptible particles will be turned over and agitated to facilitate the separation.
9. In an ore concentrator, the combination 55 with a dressing table and means for imparting differential reciprocating movements thereto and for feeding the ore over the same to effect stratification and separation of the particles of different specific gravity, of means for creating concentrated magnetic ﬁelds of alternating polarity movable with the table in one direction only, whereby the magnetically susceptible material will be turned over, agitated to facilitate the separation of the particles and the feeding of the same over the table assisted. 60
10. In an ore concentrator, the combination 65 with a slightly inclined dressing table having in succession stratifying and dressing zones, with means for feeding the ore over said table to effect stratification and separation of the ore particles of different specific gravity and strips of magnetic material incorporated in the table and having parallel longitudinally arranged terminal edges of relatively small area, of ﬁxed magnets having pole terminals with extended faces in proximity to the surface of the table whereby elongated magnetic ﬁelds are formed in the ore path with the lines of force converging toward the ore supporting 70 surface of the table, substantially as described.
11. In a concentrator, the combination 75 with a ﬁxed magnet having a pole terminal provided with a substantially flat face of extended area, of a horizontally movable dressing table mounted in proximity to the face of the pole terminal and having in succession stratifying and dressing zones, and also having incorporated therein strips of magnetic material with narrow terminal edges located at the level of the ore supporting surface in proximity to the face of the pole terminal of the magnet. 80
